(57) **CLAIM**

The ornamental design for an adjustable sofa chair, as shown and described.

DESCRIPTION

FIG. 1 is a front perspective view of an adjustable sofa chair in an open configuration with a tray in a usable positioning and a cover draped partially across the middle section of the adjustable sofa chair, showing my new design;

FIG. 2 is a left side elevational view thereof;

FIG. 3 is a right side elevational view thereof;

FIG. 4 is a front elevational view thereof;

FIG. 5 is a rear elevational view thereof;

FIG. 6 is a top plan view thereof;

FIG. 7 is a bottom plan view thereof;

FIG. 8 is a front perspective, partially exploded view of the right side crown and the left side crown with the tray rotated 180 degrees in a non-usuable positioning and the cover removed from the middle section of the adjustable sofa chair; and,

FIG. 9 is a front perspective view of the adjustable sofa chair in a closed configuration with the cover draped across the length of the sofa.

The broken lines in FIG. 8 showing a small piece underneath the left side crown depict portions of the adjustable sofa chair that form no part of the claimed design.

The stippling in the drawings depict a contrast in material and appearance.
